PROCESS OF STERILIZING

Filed Jan. 17, 1918

Inventor:
David Crowther.

By *A. Whitley*
his Attorney.

UNITED STATES PATENT OFFICE

DAVID CROWTHER, OF MINNEAPOLIS, MINNESOTA

PROCESS OF STERILIZING

Application filed January 17, 1918. Serial No. 212,319.

My invention relates to a process of sterilizing organisms. It relates more particularly to a process of sterilizing material for foods and medicines, such as flesh, milk, 5 vaccine material, etc.

I subject the organisms or material which it is desired to sterilize to an inert gas under a high degree of pressure. I may employ any of the inert gases such as nitrogen or 10 hydrogen for this purpose, but I prefer to use carbon dioxide since I have found that this gas is effective for my purpose at a lower pressure than that required for any of the other gases which I may employ. I 15 have found by experiment that various organisms when subjected to carbon dioxide at a pressure of 800 to 900 lbs. per square inch above atmosphere will become super-saturated. The molecules of the gas being 20 smaller than those of the organisms to be sterilized, will penetrate to the interior of such organisms in the course of time when sufficient pressure is applied and cause super-saturation. Then by suddenly releasing 25 the pressure the large increase in the volume of the gas inside the organism will burst its structure with complete destruction of all life contained therein. Thorough sterilization is thus accomplished without the application 30 of heat. The accompanying drawing shows a simple form of apparatus which I may employ in carrying out my process.

Referring to the drawing, a receptacle 1 has an opening 2 at one end by which it 35 may be connected with a supply of gas such as carbon dioxide. The other end of the receptacle is closed except for a small passage 3. A cap 4 containing a chamber 5 is externally screw threaded upon the receptacle 1 at 6. A closure member 7 carried by the cap is adapted to securely close the passage 3 when the cap is screwed into place. Leading into the side of the member 7 is an opening 8 which extends to the center thereof and then extends outwardly in an axial line through the outer end of this member.

In carrying out my process the material to be sterilized is placed in the receptacle 1 50 and is subjected to the inert gas introduced

through the opening 2 under the proper pressure, the cap 4 being screwed down so as to close the passage 3. When the material has become super-saturated with the gas the cap is unscrewed and the pressure 55 being suddenly released the material is subjected to bursting strain with consequent destruction of all life contained therein.

The advantages of my process are obvious. Thorough sterilization is obtained in a simple and efficient manner without the application of any heat.

I claim:

1. The process of sterilizing which consists in subjecting material to a gas which 65 is inert with relation to the material being treated under pressure for a period of time sufficient to cause the organisms in the material to become saturated, and then suddenly releasing the pressure whereby the sudden 70 expansion of the gas within the organisms will disrupt the same.

2. The process of sterilizing which consists in subjecting material to carbon dioxide under pressure for a period of time sufficient 75 to cause the organisms in the material to become saturated, and then suddenly releasing the pressure whereby the sudden expansion of the gas within the organisms will disrupt the same.

In testimony whereof I hereunto affix my signature.

DAVID CROWTHER.
